Primary Examiner—Theodore M. Shooman*Assistant Examiner*—C. Tuttle*Attorney, Agent, or Firm*—Bill D. McCarthy[57] **CLAIM**

The ornamental design for tweezers, as shown and described.

DESCRIPTION

FIG. 1 is a perspective view of tweezers showing my new design;

FIG. 2 is a plan view of the top end thereof, a plan view of the bottom end being a mirror image of FIG. 2;

FIG. 3 is an elevational view of one side thereof, an elevation view of the other side being a mirror image of FIG. 3;

FIG. 4 is an elevational view of the front end thereof; and,

FIG. 5 is an elevational view of the rear end thereof.
